UNITED STATES PATENT OFFICE.

JOHN C. LINCOLN, OF CLEVELAND, OHIO.

BRUSH-HOLDER.

1,090,159.

Specification of Letters Patent. Patented Mar. 17, 1914.

Application filed July 19, 1911. Serial No. 639,433.

To all whom it may concern:

Be it known that I, JOHN C. LINCOLN, a citizen of the United States, resident of Cleveland, county of Cuyahoga, and State 5 of Ohio, have invented a new and useful Improvement in Brush-Holders, of which the following is a specification, the principle of the invention being herein explained and the best mode in which I have contemplated applying 10 that principle, so as to distinguish it from other inventions.

My invention relates to a brush-holder, and more particularly to an adjustable feature in conjunction with improved details of 15 construction.

The object is the provision of a device of this general character which, while entirely simple and economical of manufacture, will nevertheless insure increased efficiency.

20 The said invention consists of means which are hereinafter fully described and particularly pointed out in the claims.

25 The annexed drawings and the following description set forth in detail certain means embodying my invention, the disclosed means, however, constituting but one of various mechanical forms in which the principle of my invention may be applied.

In said annexed drawings:—Figure 1 is a 30 side view of a brush-holder embodying my invention. Fig. 2 is a top plan of one extremity thereof. Fig. 3 is a section on line III—III of Fig. 2, looking in the direction of the arrows. Fig. 4 is a perspective 35 view of one detail.

The construction comprises a primary supporting yoke A which is concentric with and supported by means of a set-screw a' to the 40 commutator B. The yoke comprises, for the purposes of illustration in this instance, two diametrically opposite extensions a², each of which is provided with an open rectangular slot a³. A pair of exactly similar supporting brackets C are fixedly secured in these 45 slots through the medium of the washers c' and nuts c².

In the course of the subsequent description by reason of the fact that the individual brackets are identical, only one will be 50 described, and hence but one such bracket will be hereinafter referred to. This bracket is thoroughly insulated from the yoke by means of the insulation D interposed on either side of the yoke, and the insulation D'

disposed within the slot a³, as best seen in 55 Fig. 2.

The bracket C projects forwardly across the commutator, and is formed with a rectangular radially disposed socket opening c³. Extending from the bracket, and as shown 60 contiguous the central portion of the socket opening c³ is an arm c⁴. This arm is provided near its extremity with a transverse plain opening c⁵ and also with a second plain opening c⁶ perpendicular to and intersecting 65 this opening, as very clearly seen in Fig. 3. A stud E extends through the opening c⁵, and is provided therein with a depressed worm-threaded portion e'. This stud projects on either side of such opening, and is 70 provided in each of its ends with a flat open slot e² clearly appearing in Figs. 2 and 4. An adjusting screw F is normally seated in the opening c⁶, and by reason of the intersection of this opening with the opening c⁵ is 75 adapted to mesh with the worm threads e', as clearly seen in Fig. 3. It will accordingly be apparent that a rotation imparted to the adjusting screw F will be transmitted 80 to the stud E.

A pair of carbon brushes G having a contact area ample for the current to be commutated, are slidably seated in the rectangular opening c³, and are each electrically connected with the bracket by means of the flexible 85 copper leads H, which may be secured by means of the screw h'. A pair of spiral springs K, in this case preferably of flat metal, surround each projecting end of the stud E and have their inner ends h' fixedly 90 secured in the slots e². These springs K have their outer free extremities h² normally bearing against the outer ends of the carbon brushes G, as most clearly appearing in Fig. 2. It should now be obvious that when 95 the rotation of the adjusting screw F is imparted to the rotatable stud E, the latter will tend to either increase or diminish the degree of tension existing in the spiral springs K, and accordingly the degree of 100 pressure exerted upon the outer ends of the carbon brushes. Accordingly, an adjusting feature of my brush-holder is provided through the simple manipulation of a single screw, whereby the pressure upon the 105 brushes may be regulated to be practically uniform throughout their efficient use.

As will be readily appreciated by those

sufficiently skilled in the art, the tension in the spiral springs K may be increased by a forward turning of the screw F, and the tendency of such springs to uncoil and occasion a reverse movement be mechanically precluded. Furthermore, by reason of the fact that the worm-threaded portion e' of the stud E is depressed within its peripheral surface, this mechanical preclusion is 10 found applicable also as against any tendency of the stud to move in the direction of its own axis.

Having fully described my invention, what I claim and desire to secure by Letters 15 Patent is:—

1. A brush-holder comprising a bracket having a plain opening, a brush movably secured to said bracket, a stud rotatably mounted in said opening and provided 20 therein with a worm-threaded portion, such portion being depressed within the peripheral surface, a spiral spring secured to said stud and having its free end bearing

against said brush, and means comprising a screw in mesh with such worm-threaded portion and adapted to adjust said stud. 25

2. In a brush-holder, an arm provided with a plain transverse bore or opening, a cylindrical stud mounted in said opening as a bearing, that portion of said stud within said opening being provided with worm-wheel threads; said arm being provided with a second plain opening or bore intersecting said first named opening or bore; a worm screw loosely mounted in said second opening or bore and engaging the threads of said stud; and two spiral springs having their inner ends secured respectively to opposite ends of said stud, the opposite ends of said springs being adapted to bear upon 35 the brush.

Signed by me, this 17th day of July, 1911.

JOHN C. LINCOLN.
